(57) **CLAIM**

The ornamental design for a barbell plate, as shown and described.

DESCRIPTION

FIG. 1 is a front elevational view showing a first embodiment of my new design for a barbell plate;

FIG. 2 is a side elevational view of my barbell plate;

FIG. 3 is a cross sectional view of my barbell plate taken along the plane indicated by 3—3 in FIG. 1;

FIG. 4 is a front perspective view of my barbell plate;

FIG. 5 is a front elevational view showing a second embodiment of my new design for a barbell plate;

FIG. 6 is a side elevational view of my barbell plate;

FIG. 7 is a cross sectional view of my barbell plate taken along the plane indicated by 7—7 in FIG. 5;

FIG. 8 is a front perspective view of my barbell plate;

FIG. 9 is a front elevational view showing a third embodiment of my new design for a barbell plate;

FIG. 10 is a side elevational view of my barbell plate;

FIG. 11 is a cross sectional view of my barbell plate taken along the plane indicated by 11—11 in FIG. 9;

FIG. 12 is a front perspective view of my barbell plate;

FIG. 13 is a front elevational view showing a fourth embodiment of my new design for a barbell plate;

FIG. 14 is a side elevational view of my barbell plate;

FIG. 15 is a cross sectional view of my barbell plate taken along the plane indicated by 15—15 in FIG. 13;

FIG. 16 is a front perspective view of my barbell plate;

FIG. 17 is a front elevational view showing a fifth embodiment of my new design for a barbell plate;

FIG. 18 is a side elevational view of my barbell plate;

FIG. 19 is a cross sectional view of my barbell plate taken along the plane indicated by 19—19 in FIG. 17; and,

FIG. 20 is a front perspective view of my barbell plate.

The opposite side of the barbell plate shown in FIGS. 1, 5, 9, 13 & 17 is the mirror image thereof.
